UNITED STATES PATENT OFFICE.

ANTHONY VANDERVELD, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

LOCKING DEVICE FOR DISPLAY-RACKS.

1,243,015.

Specification of Letters Patent. Patented Oct. 16, 1917.

Application filed October 18, 1913, Serial No. 795,928. Renewed June 10, 1916. Serial No. 103,017.

To all whom it may concern:

Be it known that I, ANTHONY VANDERVELD, a citizen of the United States, and a resident of the city of Grand Rapids, in the county of Kent and State of Michigan, have invented a certain new and useful Locking Device for Display-Racks, of which the following is a specification fully disclosing a complete and operative embodiment of the same.

This invention relates to display racks of the rotatable type which have supporting portions for carrying articles suspended therefrom for exhibition and similar purposes, the said parts being rotatable to present different portions thereof to front position for easy access. The invention consists in new and useful locking means for holding the rotatable portions in place with reference to a support therefor, the locking means being manually operable for accomplishing the unlocking of the rack and permitting its rotation on its support. The locking means is also automatically operable to lock the rotatable portion of the rack in place on the attainment of certain positions of the rotatable portion with reference to its support, and with reference to a case or compartment in which the rack may be mounted. As one place where such construction is very useful, I have shown the rack as located within a show case having parallel back and front and parallel sides, and the rack supporting elements consisting of rods or bars located in parallelism, the locking means being operative when the rods or bars come into position parallel with the back of the case, though the device in question is applicable to racks whether or not they are mounted in cases or compartments. It is also a feature of my invention that the manual operation of the locking means may take place at a plurality of positions on the rack, and that whatever the portion of the rack presented to the front for inspection and access thereto, a means of manual operation of the rack will also be presented for operation thereof to unlock the rack for rotation. These purposes and functions and novel features, together with many others not specifically enumerated will be apparent on understanding being had from the following detailed description of the structure illustrated in the drawings in which,

Figure 1 is a plan view of the rack supplied with my novel locking device. 55

Fig. 2 is a side elevation thereof, the rack being indicated as mounted in a show case, the outline thereof being shown in dotted lines. 60

Fig. 3 is a sectional view of the upper portion of the rack and locking device, the section being on line a—a Fig. 1.

Fig. 4 is a section taken longitudinally and horizontally of one of the rack bars, a fragment of the bar only being shown. 65

Fig. 5 is a similar sectional view with the locking device manually operated to unlock the rack.

Similar reference numerals refer to similar parts throughout the several views of the drawing. 70

In the embodiment of the invention shown in the drawings, there is provided a tubular post 1 which is connected in any suitable manner to a supporting base, in this instance by a casting 2 in which the lower end of the post is fixed and which is secured to a carriage member 3 mounted on suitable tracks in the lower part of a case or compartment 75 80 as indicated in dotted lines in Fig. 2, the carriage member having rollers 4 which are adapted to traverse such tracks and enable the carriage member and rack to move back and forth in the case or compartment. 85 Within the post and rotatable therein is the spindle 5, the lower end of which rests on a plate 6 located below the end of the post and carried by the casting 2, shown in dotted outline in Fig. 2. At its upper end the 90 tubular post may be provided with a collar 7 in the upper side of which are formed two notches 8, located directly opposite each other in the collar. A sleeve or collar 9 is slidably mounted on the spindle 5 and is 95 made to rotate therewith through the medium of a pin 10 fixed to the spindle and extending outward through a slot 11 in the collar, the collar thereby being permitted movement up and down on the spindle with 100 in limits prescribed by the pin and slot but held to rotate with the spindle. On the lower edges of collar 9, a pair of diametrically opposed projections 12 are formed and are adapted to seat in the notches 8 of collar 7. When so seated, the collar 9 is held 105 from rotary movement, and the spindle is also held in stationary position with refer-

ence to the collar 7 and post 1, and as long as the projections and notches are so engaged, there can be no rotary movement of the spindle and of parts attached thereto.

- 5 Secured to the upper end of the spindle 5 a short distance above the collar 9 is a head 13 from which projects four arms 14 substantially radially and at the ends thereof are attached the rods or bars 15 parallel to each other and spaced apart as shown. 10 The rods or bars 15 are adapted to support and carry garment hangers of any preferred type from which may depend ready-made garments in position for ready inspection 15 and display and readily removable therefrom.

A pair of bell-crank levers 16 are pivotally mounted on the head 13, each comprising an upwardly extending arm and a horizontal arm, said horizontal arms extending outward from the head in opposite directions and each having a link 17 pivotally attached thereto, said links extending downward and being secured at their lower ends to the collar 9 by means of the ears 18 integral therewith as shown. To each upwardly extending arm of the bell crank levers a link 19 is pivotally attached and the links extend outwardly in directions opposite to each other and terminate within the rods or bars 15 which are hollow and which are perforated to receive the flattened ends 20 of said links 19. With the collar 9 in normal position with projections 12 seated in notches 8, the ends of links 19 reach to the sides of the rods 15 opposite the sides through which entrance is had to the rods, and it is evident that the parts normally occupy such positions through the weight of collar 9 tending 40 to seat the projections in the notches.

As a means of elevating the collar 9 and freeing the notches 8 of the projections 12 thereon through movement given to one of the links 19, I have provided the following structure. Projecting in either direction from the end 20 of the links 19 within the rods 15 are a pair of sheet metal members 21, and near one end of each of such members there is provided a handle member 22 located on the outside of the rod 15 and projecting horizontally therefrom, said handle being secured to the member 21 by the pin 23 extending through slot 24 in the rod 15. A short distance from the end 20 of link 19, said sheet metal member is given a quarter turn and a portion is cut away as at 25 and the extreme end fashioned with an inclined point 26, which passes a very little way under the end of part 20 on one side thereof. 55 The companion member 21 on the other side is similarly formed and its pointed end is seated in similar manner with relation to the other side of the portion 20. The shoulder at 27 formed by cutting away the member 21 serves as a seat for the spring 28 which at

its other end rests against a projection 29 secured to the side of the rod 15 and projecting therein. Spring 28 is normally under compression and works to force members 21 away from the end 20 of link 19, and forcing 70 the handle 22 to its extreme of movement defined by the boundary of slot 24, as shown in Fig. 4. There are four of these members 21, one on each side of the link ends 20, and all are similarly constructed and mounted in 75 the rods 15 so that whichever rod is presented at the front of the rack, there is presented to the operator two handle members which he may grasp to operate the locking device for unlocking and freeing the rack for 80 rotation. The positioning of the handles 22 on the rods 15 is a matter of choice and they may be located at any desired distance from the middle point of the rods, there being shown in Fig. 1 varying locations of the 85 handles.

With the rack within a case or compartment, it is desirable that the rods 15 be parallel to the back of the case and the relation of the collars 7 and 9 and notches and projections 8 and 12 is such that with the projections seated in the notches and the rack locked from rotation, the rods are held parallel to the back of the case. When drawn forward therein and access to the articles 90 held by the rear rod is desired, the rack must be unlocked and rotated. The unlocking is accomplished by grasping either handle 22 presented on the front bar and pressing it toward the middle of the bar. Such operation causes the member 21 to move lengthwise of the bar, compressing spring 28 and forcing inclined end 26 of said member 21 under the end of link 19 thereby operating it toward the center of the 105 head 13, turning the bell crank lever attached thereto about its pivot and elevating the horizontal arm thereof and elevating link 17 and the collar 9 attached thereto and thereby carrying projection 12 above the 110 notch 8 and disengaging therefrom. The elevation of the collar 9 correspondingly elevates the other link 17 and draws the other link 19 inward but there is nothing to interfere and prevent such movement, it taking place without causing any appreciable extra effort. The rack may now be rotated the projections 12 riding on the upper surface of collar 7 between the notches or depressions therein until the rack has rotated 115 through half a circumference and the projections again come into juxtaposition with the notches and seat therein such seating taking place through the influence of the weight of the collar 9, the spring 28 having 120 moved the operating member 21 to its normal position shown in Fig. 4 and permitting the link 19 to enter the rod 15 and occupy its usual position. The operation is the same whichever of the handles 22 are used, 130

any one of the members 21 by its longitudinal movement serving to effect the elevation of the collar 9 to unlock the rack.

The above described construction while practically operative and complete is not to be considered other than a diagrammatic representation of the invention, and in no sense as limiting the invention to any particular specific construction. The invention is defined in the claims, and all modifications in structure properly falling within the scope thereof, are to be considered as comprehended in my invention.

What I claim as new and desire to secure by Letters Patent is:—

1. In combination, a support, a rack member mounted thereon for rotation, said rack member including parallel rods, means for locking the rack member in fixed relation to the support, a plurality of separate means mounted on the rack member and independently associated with the locking means for manual operation thereof to free the rack for rotation, each of said manually operated means including a device mounted within said rods and mounted to move lengthwise thereof and engaging elements of the locking means and operating the same to unlock the rack and free it for rotation on such lengthwise movement.

2. In combination, a support, a rack member mounted thereon for rotation, said member including parallel rods, means for locking the rack member in fixed relation to the support, means for manually operating said locking means to unlock and free the rack for rotation, said locking means having elements connected thereto and extending to the rods, and said manually operated means including elements mounted on and movable longitudinally of the rods and engaging with the said connected elements, said elements of the operating means being formed to move the said connected elements on longitudinal movement of the operating elements in one direction and thereby operate the locking means to free the rack for rotation.

3. In combination, a support, a rack member mounted thereon for rotation, said rack member including parallel rods, and a centrally located head, means to lock the rack member in fixed relation to its support, devices mounted on the head, connections between said devices and the locking means, connections leading from said devices to the rods, means mounted on the rods and movable lengthwise thereof and having operative engagement with the connections leading to the rods whereby when said means is moved longitudinally of the rods, the said devices mounted on the head are operated and thereby operate the locking means to unlock and free the rack for rotation.

4. In combination, a support, a rack member mounted thereon for rotation, said rack

member including a centrally located head and a plurality of article supporting elements attached to and movable therewith, means to lock the rack member against rotation, means mounted on the head and movable thereon, connections between said means and the locking means, connections leading from said means to the article supporting elements, and a plurality of cam devices mounted on said article supporting elements and independently manually operable, said cam devices having engagement with the connections leading to the article supporting devices whereby when manually operated the said connections are moved and serve to operate the locking means to free the rack for rotation.

5. In a device of the character described, a rack member mounted for rotation, said rack member including a centrally located head and rods attached to and movable therewith, locking means for holding the rack from rotation, bell-crank levers mounted on the head, connections leading therefrom to the locking means whereby the movement of either of the bell-crank levers will serve to unlock the rack for rotation, links attached to said levers and leading to the rods, separate means mounted on the rods and movable lengthwise thereof, said means engaging the links, each of said separate means where it engages its respective link being formed to move said links with the longitudinal movement of any of the separate means and thereby operate the connected bell-crank levers to operate the locking means and free the rack for rotation.

6. In combination, a support, a rack member mounted thereon for rotation, said rack member including an upright spindle and article supporting bars connected thereto and arranged parallel to each other, a fixed locking member connected to the support, a locking member movably mounted on the spindle, locking means on said locking members adapted to engage and lock the rack against rotation, and a plurality of separate devices mounted on said parallel bars and movable longitudinally thereof, said devices having operative connection with the movable locking member whereby the longitudinal movement of any one thereof will move said movable locking member away from the fixed locking member, disengage the locking means thereon and free the rack for rotation.

7. In combination, a support, a rack member mounted thereon for rotation, said rack member including a spindle, a head attached thereto, arms extending from the head and rods carried by the arms in parallel relation spaced apart and lying on opposite sides of the head, a fixed locking member on the support, a movable locking member on the spindle, bell-crank levers mounted on the

head and each having connection with the movable locking member, links leading from the bell-crank levers in opposite directions to and into the rods, members located within 5 the rods to either sides of said links and mounted to move longitudinally of the rods, cams on said members engaging with the links whereby on movement of any of said members, the links will be operated longitudinally and through the bell-crank levers 10 and connections therefrom to the movable

locking member, will operate said locking member to free the rack member for rotation.

In testimony whereof, I have hereunto 15 affixed my signature in the presence of two witnesses.

ANTHONY VANDERVELD.
